KARL EVALD NORDLING AND RUBEN RAGNAR BENEDICTUS BENGTZON, OF ÅMÅL,
SWEDEN.

TWISTED BOILER-TUBE.

1,315,853.

Specification of Letters Patent. Patented Sept. 9, 1919.

Application filed April 29, 1919. Serial No. 293,568.

To all whom it may concern:

Be it known that we, KARL EVALD NORDLING and RUBEN RAGNAR BENEDICTUS BENGTZON, citizens of Sweden, residing at Åmål, 5 in the county of Älfsborg, Sweden, have invented certain new and useful Improvements in Twisted Boiler-Tubes, of which the following is a specification.

Twisted or spirally rolled boiler tubes 10 have of late been used more and more on account of a better utilization of fuel and the effective spark arresting attained in many cases. It has however been demonstrated, that the efficiency of the spiral form 15 cannot be maintained as it is practically impossible to remove the gradually increasing deposits of soot in the wave-troughs, that the resistance to the passage of the combustion products is too great, and the tubes 20 have a considerably less stiffness than corresponding smooth tubes.

The object of the present invention is to remedy these defects and also to increase the efficiency of the spiral form of tube.

25 In the accompanying drawing Figures 1-6 show some forms of the invention. Figs. 1-3 are longitudinal sections of single threaded, double threaded and triple threaded tubes. Figs. 4-6 are corresponding cross- 30 sections perpendicular to the longitudinal direction of the tubes. For the sake of comparison Fig. 7 shows a cross-section of a common single threaded tube having a uniform wave profile in the longitudinal section. Figs. 8 and 9 show the cross-sections of double and triple threaded tubes having a similar longitudinal profile, if such tubes existed. All figures show tubes of equal diameter, thickness and depth of thread, and 35 thus they may be directly compared.

40 Tubes according to the invention are characterized by the following features.

In the longitudinal sections, Figs. 1-3, the inwardly directed threads 1 do not ad- 45 join each other directly, but are connected with each other by means of straight or eventually slightly bent portions 2 of the tube. In the cross-section, Figs. 4-6, these portions 2 are to be found as material lo- 50 cated at the circumference or in the proximity thereof, while the threads 1 clearly appear as wave-like inwardly bent portions of the tube material. In each of these bends

the inwardly directed curve together with the curves connecting the first mentioned 55 curve with the straight portions 2 take up so great a part of the circumference that the corresponding angle of center 3 is greater than 45°. In this way the inwardly bent portion will obtain such an extension in the 60 cross-section that feasibly not more than three are contained in the same section, and thus the number of threads is limited to a maximum of three. The angle 5 formed by the common tangents 4 to the inwardly di- 65 rected curve and to the two intermediate curves connecting said curve with the outer surface of the pipe is obtuse. The sectional form thus defined implies that the inside diameter D of the tube, the depth H 70 and the length L of the threads as well as the pitch P are dependent of each other within certain limits.

By providing the portions 2 between the threads there is gained, as is clearly shown 75 by comparing Figs. 4-6 with Figs. 7-9, the condition that the sectional area of the gas current will be increased which results in a reduced resistance to the passage of the combustion gases, that the circumference 80 will be enlarged which results in an increased heating surface and an increased efficiency of the boiler, and that the cross-sections of the tubes will have a greater moment of inertia and thus an increased 85 stiffness. By introducing the wave-like bending inward of the threads in the cross-section and the limitation of the angle 3 the condition is gained that the line enclosing the sectional area of the gas current, 90 i. e. the gas profile, will be given a form that even in single threaded tubes and still more in double or triple threaded tubes guarantees the helical movement of the gases. The limitation of the angle 5 excludes 95 U-shaped or similar unsuitable thread profiles in which it is difficult to avoid a reduction of the thickness of the material in the threads, in which latter impurities from the water in the boiler are easily collected. 100 The simultaneous presence of the threads 1, that are bent wave-like inwardly in the longitudinal section, and of the straight or slightly bent portions 2 results in a lower limit for the pitch of the threads, by which 105 the resistance of flow in the tubes is fur-

- ther limited and the twisting of the flow of gases is promoted in such a way that the latter may follow the spiral form without slipping over the wave-crests, which is the case in tubes with the small pitches hitherto known. This limitation of the pitch makes it also possible to remove deposits of soot in the wave-troughs between the threads by means of blowing or brushing out.
- 10 In tubes according to the invention the disadvantages incident to tubes of the construction hitherto known are substantially removed and the efficiency of the helical form is essentially increased. The flue gases are forced by the efficacious rotation intimately to come in contact with the tube walls all around the same during an active exchange of heat with an increased efficiency of the boiler, and the fuel particles crumble 20 away simultaneously by the rubbing against the tube walls. This takes place with a comparatively insignificant resistance to flow. The cross-sections insure necessary rigidity to the tubes. The great pitch prevents deposits of soot in the wave-troughs 25 between the threads, and makes it possible to clean the tubes thoroughly by blowing-

or hand-tools. Thus it is possible always to maintain the efficiency of the screw form.

Of course, the profile and the depth of the threads etc. may be varied without departing from the characteristic features of the invention as stated.

Having thus described our invention, what we claim as new and desire to secure by Letters Patent is:—

A screw shaped boiler tube in which the inwardly directed threads are spaced from one another by unaltered portions of the tube wall, said threads forming a plurality of wave-like recesses in the tube limited to not more than three, each recess having such a shape that its subtended angle is greater than 45° and that the tangents common to said first mentioned curve and the adjacent curves form an obtuse angle with each other.

In testimony whereof, we have signed our names to this specification in the presence of two subscribing witnesses.
